(No Model.)

L. E. JONES.

NAME.

No. 273,096.

Patented Feb. 27, 1883.

FIG. 1.

WITNESSES.

John Smith
J. T. Brewster, Jr.

INVENTOR.

Leavellyn E. Jones

UNITED STATES PATENT OFFICE.

LLEWELLYN E. JONES, OF SYRACUSE, NEW YORK.

HAME.

SPECIFICATION forming part of Letters Patent No. 273,096, dated February 27, 1883.

Application filed December 14, 1882. (No model.)

To all whom it may concern:

Be it known that I, LLEWELLYN E. JONES, of Syracuse, in the county of Onondaga and State of New York, a citizen of the United States, have invented certain new and useful Improvements in Hames, of which the following is a specification, reference being had to the accompanying drawing, in which is shown a longitudinal section of the upper part of a hame.

My invention relates to that kind of hames known to the trade as "iron-bound wooden hames," or hames in which the wood is surrounded by a strap of iron.

It consists in fitting the iron around the edge of the wooden body of the hame without welding the ends of the iron together, but simply lapping one end over the other and holding them together by a rivet through them and through the hame, a recess being provided in the wooden body, on one edge, to receive one end of the iron, and thus diminish the projection of the lap-joint outwardly.

It is constructed as follows:

A is the wooden body of the hame, constructed of the usual form and size, except that it has the recess D upon one edge, usually upon the back of the hame, near or adjacent to the upper end. I generally make this recess of the same depth as the thickness of the iron used around the hame.

B is the binding-iron, bent to the proper shape to fit around the body A, and of such length that it will surround the body, and the two ends C F will overlap one over the other, as shown in the drawing, the end C lying in

the recess and the end F lapping over upon the end C.

E is a rivet through the lap, the body A, and iron B, opposite to the lap, to hold all of the parts together securely. By means of the recess D the outward projection of the lap-joint is diminished. By this mode of construction the binding-iron B can be fitted to the wood easier, quicker, and with greater certainty of a perfect fit than where the ends of the iron are welded together before being placed around the wood. I usually drill the holes for the rivet E after the iron has been perfectly fitted around the wood A, and the insertion of the rivet secures the whole together in a most perfect manner. The recess D can be made of less depth than the thickness of the iron, or entirely dispensed with, if desired, the lap-joint being retained, however.

The drawing shows only a portion of the hame covering my invention, the balance being of any ordinary construction.

What I claim as my invention, and desire to secure by Letters Patent, is—

A hame bound with a continuous strap of iron, one end of which is embedded in a recess in the hame, the other overlapping the embedded end, and secured in place by a rivet or bolt passing through the ends and into the hame, all substantially as described.

In witness whereof I have hereunto set my hand this 24th day of October, 1882.

LLEWELLYN E. JONES.

In presence of—

C. W. SMITH,

T. T. BREWSTER, Jr.
